COMBINATION BUMPER AND STEP FOR A PICK-UP TRUCK

Francis L. Struben, 8301 Philadelphia Road,
Baltimore, Md. 21206

Filed June 21, 1967, Ser. No. 7,536

Term of Patent 14 years

(Cl. D14—6)

FIG. 1

FIG. 2

FIG. 6

FIG. 1 is an upper front perspective view of a combination bumper and step for a pick-up truck incorporating my new design;
 FIG. 2 is a lower rear perspective view thereof;
 FIG. 3 is a top plan thereof;
 FIG. 4 is a rear view thereof;
 FIG. 5 is a bottom plan thereof; and
 FIG. 6 is a section to an enlarged scale taken along line 6-6 of FIG. 4.

What I claim is:

The ornamental design of a combination bumper and step for a pick-up truck, as shown.
